No. 854,989.

PATENTED MAY 28, 1907.

W. E. EDWARDS.
POCKET AND OTHER CASE.
APPLICATION FILED APR. 9, 1906.

UNITED STATES PATENT OFFICE.

WILLIAM E. EDWARDS, OF IRVINGTON, NEW JERSEY, ASSIGNOR OF ONE-HALF TO AUGUST O. SCHUSTER, OF NEWARK, NEW JERSEY.

POCKET AND OTHER CASE.

No. 854,989.

Specification of Letters Patent.

Patented May 28, 1907.

Application filed April 9, 1906. Serial No. 310,735.

To all whom it may concern:

Be it known that I, WILLIAM E. EDWARDS, a citizen of the United States, residing at Irvington, in the county of Essex and State of New Jersey, have invented certain new and useful Improvements in Pocket and other Cases; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My present invention has reference to improvements in pocket or other suitable cases for the placing therein of cigarettes, but which are also applicable to other uses, such as the carrying therein of surgical instruments, medicine vials, and similar articles.

The invention relates, more particularly, to a novel construction of pocket or other case provided with a supporting plate pivotally arranged upon the hinge-pin or rod of the case, said supporting plate being adapted to receive cigarettes, or similar articles, and means connected with the said supporting plate for retaining or holding the said cigarettes upon the said supporting plate.

The principal object of this invention therefore is to produce a pocket or other case for the purposes above enumerated which shall be neat in appearance and shall be of a simple, strong, and durable construction, thus providing a case for more readily presenting the articles therein for removal, by means of the automatically operated supporting plate which swings in an upward direction and above the front edge of the case when the same is opened.

My present invention therefore consists in the novel construction of pocket or other case embodying the principles hereinabove mentioned, and of a character to be more fully described in the following specification.

This invention consists, furthermore, in the several novel arrangements and combinations of the various parts, as well as in the details of the construction of the same, all of which will be hereinafter more fully set forth, and then finally embodied in the clauses of the claims, which are appended to this specification.

The invention is fully illustrated in the accompanying drawings, in which:—

Fig. 1 is a plan or top view of the pocket case in its closed position. Fig. 2 is a plan or top view of the pocket case in its open position. Fig. 3 is a vertical cross section of the pocket case in its closed position, said section being taken on line 3—3 in the said Fig. 1. Fig. 4 is a vertical cross-section of the pocket case in its closed position, taken on line 4—4 in the said Fig. 1, the cigarettes shown in Figs. 2 and 3 being removed. Fig. 5 is a similar view illustrating the pocket case in its open position, the cover of the case being shown partly broken away.

Similar characters of reference are employed in all of the said above described views, to indicate corresponding parts.

Referring now to the said drawings, the reference-character 1 indicates the complete case, which consists, essentially, of a body section 2 provided with a laterally and inwardly projecting flange 3, which extends around the three sides of the body section 2 from any ordinary form of spring-hinge 4, which pivotally connects with the said body-section 2 a cover-section 5. This cover-section 5 is also provided with a laterally and inwardly projecting flange 6, extending around three sides of the cover-section 5 from the said spring-hinge 4.

For the purpose of retaining or holding the said body section 2 and the cover section 5 in their closed relation, there is provided a lock-plate 7 having a nose-piece or catch 8 which normally engages with the flange 6 of the cover-section 5 when the same is closed down upon the body-section 2. The said lock-plate 7 is held in its normally locking position by means of a flat-spring 9 which extends across the rear side of the said lock-plate 7; the ends of the said flat spring 9 extending beneath the laterally and inwardly projecting flange 3, and being held in their operative engagement with the said lock-plate 7 by means of a pair of downwardly extending lugs 10 upon the said laterally and inwardly projecting flange 3. For the purpose of forming guides for maintaining the proper operation of the said lock-plate 7, there are provided a pair of lugs 11 extending laterally from the said laterally and inwardly projecting flange 3 of the body

section 2, and a correspondingly placed pair of lugs 12 extending laterally from the said laterally and inwardly projecting flange 6 of the cover-section 5, the said lock-plate 7 sliding between the said lugs 11 and 12 when operated to release the cover section 5. The lock-plate 7 is further provided with a laterally and forwardly extending finger-piece 13 which passes through an opening 14 in the front side of the body-section 2.

Pivots secured within the case 1 is a supporting-plate 15, of any desirable ornamental configuration, the said supporting-plate 15 being provided around its two sides and the rear with a wall or flange 16 extending above and beneath the said supporting plate at right angles thereto; the said wall or flange 16 in connection with the said supporting-plate 15 being adapted to form or provide receiving pockets for the insertion of cigarettes or other articles on both sides of the said supporting plate 15. To pivotally connect the said supporting plate 15 within the case 1, there is provided a laterally and rearwardly extending lug or tongue 17 secured upon the wall or flange 16 of the said supporting plate 15, so as to form an integral part thereof; but it may be connected therewith in any other desirable manner. The said lug or tongue 17 is provided at its free end with a laterally extending hole or opening 18 through which is inserted the pin or rod 19 of the hinge 4, thus pivotally connecting the said supporting-plate 15 to the case 1. The said lug or tongue 17 is further provided, where it joins the wall or flange 16 of the supporting plate 15, with an opening 20 formed by a surrounding wall or flange 21 which provides a bearing for a flat-spring 22 which passes there-through, the said wall or flange 16 being also provided with cut-away portions 23 to permit of the proper operation of the said set spring 22.

As will be readily understood from an inspection of the figures of the drawings, when the body section 2 and the cover section 5 are in their closed position, the flat-spring 22 is compressed, but when the cover-section 5 is released from its closed position, and assumes its open position, then the flat-spring 22 has a tendency to straighten out or assume its normal tension, thereby pushing open the bottom of the body section 2, or against the cover section 5, as the case may be. This causes the supporting-plate 15 to be tipped or swung in an upward direction, so that its front or open portion will project above the sides of the case 1, thereby presenting the cigarettes or other articles supported upon the said supporting plate 15 to the operator and for ready removal therefrom.

To secure or retain the cigarettes, or similar articles, upon the supporting-plate 15, there are provided retaining bars 24, one on

each side of the said supporting-plate 15. These retaining bars 24 extend longitudinally across the face of the said supporting plate 15 and are pivotally secured to the wall or flange 16 of the said supporting plate 15 by means of a pair of lugs 25 on each retaining-bar 24. Three lugs 25 are pivotally secured between another pair of lugs 26 extending from the wall or flange 16, by means of a pin or rod 27.

Arranged between the lugs 25 and upon the pin or rod 27 is a spiral-spring 28, the tendency of which is to normally hold the said retaining-bar 24 in its lowered position extending across the face of the supporting-plate 15, substantially as shown.

From the above description it will be seen that a neat and simply constructed case provided with a supporting plate pivotally arranged therein, and adapted to be automatically swung or tipped above the sides of the case, when the same is opened, has been produced, thus permitting the cigarettes or similar articles, to be readily and easily removed from the same.

I claim:

1. As a new article of manufacture, a case, comprising a body-section and a cover-section, pivotally connected by means of a spring-hinge, a supporting plate pivotally connected with the said hinge, said supporting-plate being provided at its two sides and the rear with a wall or flange extending above and beneath the said supporting-plate to form pockets or receptacles for the reception of cigarettes or similar articles, means connected with the said supporting plate for swinging or tipping the front side thereof above the sides of the case when the same is opened, and means upon said supporting-plate adapted to retain the cigarettes or similar articles thereon, substantially as and for the purposes set forth.

2. As a new article of manufacture, a case, comprising a body-section and a cover-section pivotally connected by means of a spring-hinge, a supporting plate pivotally connected with the said hinge, said supporting-plate being provided at its two sides and the rear with a wall or flange extending above and beneath the said supporting-plate to form pockets or receptacles for the reception of cigarettes or similar articles, means connected with the said supporting plate for swinging or tipping the front side thereof above the sides of the case when the same is opened, and means upon said supporting-plate adapted to retain the cigarettes or similar articles thereon, consisting of retaining bars on each side of the said supporting plate, hinged or pivotally connected to the wall or flange of the said supporting plate, and springs connected with said retaining-bars, adapted to normally retain the said retaining-bars in their positions.

extending across the face of the said supporting plate, substantially as and for the purposes set forth.

3. As a new article of manufacture, a case, comprising a body section and a cover section, pivotally connected by means of a spring-hinge, a supporting plate pivotally connected with the said hinge, said supporting plate being provided at its two sides and the rear with a wall or flange extending above and beneath the said supporting plate to form pockets or receptacles for the reception of cigarettes or similar articles, means connected with the said supporting plate for swinging or tipping the front side thereof above the sides of the case when the same is opened, and means upon said supporting-plate adapted to retain the cigarettes or similar articles thereon, and means connected with the said body-section and the said cover-section for locking or holding the said body-section and cover-section in their closed position, substantially as and for the purposes set forth.

25 4. As a new article of manufacture, a case, comprising a body-section and a cover-section, pivotally connected by means of a spring-hinge, a supporting plate pivotally connected with the said hinge, said supporting-plate being provided at its two sides and the rear with a wall or flange extending above and beneath the said supporting-plate to form pockets or receptacles for the reception of cigarettes or similar articles, means connected with the said supporting plate for swinging or tipping the front side thereof above the sides of the case when the same is opened, and means upon said supporting-plate adapted to retain the cigarettes or similar articles thereon, consisting of retaining-bars on each side of the said supporting plate, hinged or pivotally connected to the wall or flange of the said supporting plate, and springs connected with said retaining-bars, adapted to normally retain the said retaining-bars in their positions extending across the face of the said supporting-plate, and means connected with the said body-section and the said cover-section for locking or holding the said body-section and cover-section in their closed position, substantially as and for the purposes set forth.

5. As a new article of manufacture, a case, comprising, a body-section and a cover-section, pivotally connected by means of a spring-hinge, laterally and inwardly projecting flanges on said body-section and said cover-section extending around three sides of the said body and cover sections from the said spring-hinge, means for locking or hold-

ing said body and cover sections in their closed position, consisting of pairs of guide-lugs on said laterally and inwardly projecting flanges of said body and cover sections, a lock-plate provided with a nose or catch-piece adapted to slide between said guide-lugs, said nose or catch piece being adapted to engage with the said laterally and inwardly projecting flange of the cover-section, a finger-piece extending laterally from said lock-plate through a hole or opening in the said body-section, a flat-spring extending across the rear of said lock-plate, said flat-spring being held in its normal operative relation by lugs on said laterally and inwardly extending flange of the said body-section, substantially as and for the purposes set forth.

6. As a new article of manufacture, a case, comprising a pair of hinged body-sections, means for locking the said body-sections in their closed relation, a supporting-plate pivotally connected with the hinge of the said body-sections by means of a tongue or lug, a spring-bearing in said tongue or lug, a flat spring in said spring-bearing, the ends of said flat-spring being adapted to extend above and below the said supporting-plate and to engage with the body-sections of the case, substantially as and for the purposes set forth.

7. As a new article of manufacture, a case, comprising a pair of hinged body-sections, means for locking the said body-sections in their closed relation, a supporting-plate pivotally connected with the hinge of the said body-sections by means of a tongue or lug, a spring-bearing in said tongue or lug, a flat spring in said spring-bearing, the ends of said flat-spring being adapted to extend above and below the said supporting-plate and to engage with the body-sections of the case, and a wall or flange extending around the sides and rear of said supporting-plate, and above and beneath the same, and retaining-bars on each side of said supporting-plate pivotally connected to the said wall or flange and adapted to retain cigarettes or similar articles upon the said supporting plate, and springs connected with said retaining-bars adapted to hold the said retaining-bars in their normal operative relation to the said supporting-plate, substantially as and for the purposes set forth.

In testimony, that I claim the invention set forth above I have hereunto set my hand this 4th day of April, 1906.

WILLIAM E. EDWARDS.
